CLAIM

The ornamental design for a solar garden lamp, as shown and described.

DESCRIPTION

FIG. 1 is a perspective view of the solar garden lamp showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged view of the top portion of the solar garden lamp in FIG. 1. The broken lines show portions of the solar garden lamp that form no part of the claimed design.
